CLAIM

The ornamental design for a medication inhaler spacer, as shown and described.

DESCRIPTION

FIG. 1 is a right front perspective view of a medication inhaler spacer showing our new design;

FIG. 2 is a rear elevational view thereof, the front elevational view being a mirror image thereof;

FIG. 3 is a top plan view thereof;

FIG. 4 is a bottom plan view thereof;

FIG. 5 is a right side elevational view thereof; and,

FIG. 6 is a left side elevational view thereof.
